(57) **CLAIM**

The ornamental design for a sock with multiple ring swellings, as shown and described.

DESCRIPTION

FIG. 1 is a perspective view of a sock with multiple ring swellings showing my new design;

FIG. 2 is a front elevational view thereof, the rear is a mirror image;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof with the sock in an alternate position;

FIG. 8 is a front elevational view thereof, the rear is a mirror image;

FIG. 9 is a right side elevational view thereof;

FIG. 10 is a left side elevational view thereof;

FIG. 11 is a top plan view thereof;

FIG. 12 is a bottom plan view thereof;

FIG. 13 is a front perspective view thereof with the sock in an alternate position;

FIG. 14 is a front elevational view thereof, the rear is a mirror image;

FIG. 15 is a right side elevational view thereof;

FIG. 16 is a left side elevational view thereof;

FIG. 17 is a top plan view thereof; and,

FIG. 18 is a bottom plan view thereof.
